TRACK SUPPORTING MEANS

Carl Dahlberg, Duluth, Minn., assignor of one-half to Martin J. Friedman, Duluth, Minn.

Application April 24, 1950, Serial No. 157,695

4. Claims. (Cl. 198—213)

This invention relates to axially rotatable track for transporting objects on hooks, and has special reference to a novel means for supporting such track.

In my co-pending application, Serial No. 78,871, I have disclosed an axially rotatable track having a spiral arranged on the outer surface thereof, by means of which objects on hooks may be moved along the track. It is one of the principal objects of the instant invention to provide simple and efficient means to support the track along its straight runs.

Another object is to provide a novel supporting hook for the track.

Another object is to provide a novel coupling for the individual lengths of track which functions efficiently as such and which will serve as a part of the spiral track and function efficiently in conjunction with the track support, yet will not interfere with the rotation of the track.

Another object, more specific, is to provide a saddle bearing having ball bearings mounted therein to provide a more efficient mounting for the rotatable track.

Another object is to provide a solid coupling member having means at each end thereof connecting adjacent track sections, the diameter of the coupling being the same as that of the track, and having a spiral groove therein to form a continuation of the spiral track.

These and other objects and advantages will become more apparent as the description of the invention proceeds.

In the accompanying drawing forming a part of this application:

Fig. 1 is a side elevational view of my track supporting means.

Fig. 2 is an enlarged sectional view of the invention on the line 2—2, Fig. 1.

Fig. 3 is a top plan view on the line 3—3, Fig. 1, showing the track mounted on the carrying seat of the supporting hook.

In the drawing, the reference numeral 1 indicates the threaded portion of a supporting hook or hanger 2, the threaded portion being adapted for installation on any suitable support, from a wall or ceiling for example.

The hook 2 is substantially J-shaped, as shown, and the outer end 3 thereof is enlarged and provided with a concave cradle or bearing seat 4 of substantially semi-circular cross section, the seat 4 extends across the upper end of the enlarged end 3 at right angles to the plane of the hook.

Centrally of the seat 4, a downwardly extend-

ing recessed seat 5 is provided on the hook 2, and at a right angle behind the rear end 3 of the hook 2 is a seat 6 of semi-circular cross section, the seat 6 being centrally disposed on the hook 2, and the rear end 3 of the hook 2 being disposed centrally of the seats 5 and 6. The hook 2 is provided with a shoulder 7 at the rear end 3, and the shoulder 7 is provided with a recessed seat 8, the shoulder 7 being centrally disposed between the seats 5 and 6, and the shoulder 7 being centrally disposed between the seats 5 and 6.

2. The bearing 6 is preferably of the ball bearing type and two of such placed in side by side relation are preferred. As shown, the bearings are disposed in the opening at right angles to the plane of the seat 4, thus providing an efficient seat to rotatably support the axially rotatable track.

3. The most inexpensive track for use with the instant invention comprises lengths of common pipe 8 with wire 9 wound thereon in a helix or screw, as shown, and it may be readily seen that objects hung on hooks may be moved longitudinally of the screw track by rotating the latter axially.

4. It has been a problem to support the track above described so that it will rotate freely without jumping or vibrating and without causing excessive wear to the supporting elements or to the wire spiral on the track.

5. To overcome this difficulty, I have provided a coupling member 10 which joins the individual sections of track. The coupling 10 comprises a preferably solid cylindrical member of substantially the same diameter as the pipe 8 used for the track 8—9, as shown. Each end of the coupling 10 is provided with means for connecting with adjacent track sections, preferably a threaded shank 11, as shown. Thus, a track section

30 may be threaded on each of the shanks 11 and a continuous length of track will be provided. However, the wire helix does not lend itself to contact with a track supporting device; therefore,

35 I have provided a helical groove 12 in the outer surface of the coupling member, forming a continuation of the wire screw.

40 To connect the screw groove with the wire screw of the track sections, I prefer to cut the ends of the wire 9 at an angle, as at 13, adjacent each coupling and provide a short groove 14 in the pipe in which the angularly cut end of the wire is carried. The wire used for the screw of the track sections preferably has a spring tendency so that the end 13 of the wire is biased into the groove 14 at all times. Thus, any pressure or stress which may be developed, tending to move the end 13 of the wire out of its desired position, will be overcome by the end 13 of the wire being carried in the groove 14.

45 The beveled ends 13 also will guide the hooks, indicated at 15, which are carried on the track, into the groove 14. By aligning the groove 14 with the groove 12 on the coupling, a continuous, uninterrupted travel is provided for the hooks 15 along the track from

the track on to the coupling, and, obviously, the hooks will be guided by the groove 12 across the coupling and be transferred to the wire 9 on the succeeding track section by passing from the groove 12 into the adjacent groove 14 where the hook will engage the beveled end 13 and be carried out of the groove 14 and on to the track section. The construction of the hook 2 and bearing here shown, obviously, will not interfere with the travel of hooks.

Having thus described my invention, what I claim is:

1. In a device for transporting objects on hooks, a plurality of axially rotatable sections, each of said sections comprising a length of pipe and a wire arranged helically on the surface of said pipe forming a screw conveyor; a coupling intermediate said sections, said couplings comprising a member of substantially the same diameter as said pipe, means at each end of said coupling to connect to said sections, a helical groove in said couplings forming a continuation of the screw of said pipe; and means to support said sections at said couplings.

2. In a device for transporting objects on hooks, a plurality of axially rotatable sections, each of said sections comprising a length of pipe and a wire arranged helically on the surface of said pipe forming a screw conveyor; a coupling intermediate said sections, said couplings comprising a member of substantially the same diameter as said pipe, means at each end of said coupling to connect to said sections, a helical groove in said couplings forming a continuation of the screw on said pipe; and means to support said sections at said couplings, said supporting

means comprising a hook having an upwardly disposed end portion, a bearing seat on said end portion, said seat being open upwardly whereby said coupling may be received therein.

3. The structure as set forth in claim 2 and rotatable bearings carried on said end portion and extending above said seat whereby a freely rotatable mounting is provided for said sections.

4. In a device for transporting objects on hooks, a plurality of axially rotatable sections, means coupling said sections together forming a continuous track, each of said sections having a helical thread arranged on the outer surface thereof and said thread of each of said sections being joined with that of each adjacent section to form a continuous screw conveyor, and means for supporting said track, said supporting means comprising a hook having an upwardly disposed end portion, a bearing seat on said end portion, said seat being open upwardly whereby said track may be received therein, and a rotatable bearing carried on said end portion and extending above said seat whereby a freely rotatable mounting is provided for said sections.
